[57] CLAIM

The ornamental design for a vehicle front door panel, as shown and described.

DESCRIPTION

FIG. 1 is a perspective view of a vehicle front door panel showing my new design;

FIG. 2 is a front elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a perspective view of a second embodiment of

a vehicle front door panel showing my new design;

FIG. 8 is a front elevation view of FIG. 7;

FIG. 9 is a right side elevation view of FIG. 7;

FIG. 10 is a left side elevation view of FIG. 7;

FIG. 11 is a top plan view of FIG. 7; and,

FIG. 12 is a bottom plan view of FIG. 7.

The rear of the two embodiments of the vehicle door panel is understood to be unornamented and reverse images of the front thereof.
